DESIGN FOR AN AUTOMOBILE EMBLEM PLATE

Robert A. Hall, Bronx, N. Y.

Application January 23, 1940, Serial No. 89,645

Term of patent 7 years

To all whom it may concern:

Be it known that I, Robert A. Hall, a citizen of the United States, residing at Bronx, in the county of Bronx and State of New York, have invented a new, original, and ornamental Design for an Automobile Emblem Plate, of which the following is a specification, reference being had to the accompanying drawing, forming part thereof.

I claim:

The ornamental design for an automobile emblem plate, as shown.

ROBERT A. HALL.
